UNITED STATES PATENT OFFICE.

JASPER H. STANFIELD, OF MUSKEGON, MICHIGAN, ASSIGNOR OF ONE-HALF TO JAMES HAMILTON, OF MUSKEGON, MICHIGAN.

OPERATING MECHANISM FOR WASHING-MACHINES.

No. 869,200.

Specification of Letters Patent.

Patented Oct. 22, 1907.

Application filed April 22, 1907. Serial No. 369,561.

To all whom it may concern:

Be it known that I, JASPER H. STANFIELD, a citizen of the United States, residing at Muskegon, in the county of Muskegon and State of Michigan, have invented certain new and useful Improvements in Operating Mechanism for Washing-Machines; and I do declare the following to be a full, clear, and exact description of the invention, such as will enable others skilled in the art to which it appertains to make and use the same.

This invention relates to improvements in operating mechanism for washing machines.

The object of the invention is to provide a mechanism of this character having means whereby power may be applied thereto in different ways to actuate the same.

With this object in view, the invention consists of certain novel features of construction, combination and arrangement of parts as will be more fully described and particularly pointed out in the appended claims.

In the accompanying drawings, Figure 1 is a side view of a portion of a washing machine showing the application of the operating mechanism thereto; Fig. 2 is a top plan view of the same; Fig. 3 is an end view; Fig. 4 is a longitudinal vertical sectional view; and Fig. 5 is a view similar to Fig. 3, showing the handle turned down to a position at right angles to that shown in the other figures of the drawings.

Referring more particularly to the drawings, 1 denotes the supporting frame for the operating mechanism, 30 said frame comprising a base plate, 2, adapted to be bolted or otherwise secured to the top of the washing machine. On one end of the plate 2 is arranged a vertically disposed bearing sleeve or socket 3, in which is revolvably mounted the upper end of the dasher shaft, 4; 35 said shaft projects down into the body of the washing machine, and is provided with suitable dashers or clothes washing devices, not shown. On the upper end of the shaft 4 is fixedly mounted a sprocket gear, 5.

Arranged on the plate 2 in rear of the bearing sleeve 3, 40 is an upwardly projecting vertically disposed stud shaft, 6, on which is mounted to oscillate a yoke, 7, to the ends of which are connected the opposite ends of a sprocket chain, 8, said chain being adapted to engage the sprocket gear 5, whereby when the yoke is oscillated, the chain 8 will be reciprocated, thereby revolving the sprocket gear 5, and the dasher shaft 4, first in one direction and then the other. On one side of the yoke 7 is formed a segment of a bevel gear 9, the teeth of which are adapted to be engaged by the teeth of a segmental rack, 10, 45 formed on the operating lever, 12, which is mounted at its lower end and a rightangularly projecting bearing stud, 13, said stud projecting from a lug, 14, formed on the plate 2 adjacent to its outer end.

The upper end of the operating lever 12 is provided 50 with a seat, 15, with which is adapted to be engaged the

lower end of a handle socket, 16. The lower end of the socket 16 is in the form of a head 17, which is adapted to be engaged with the seat 15 to hold the handle socket in a vertical position as shown in the first figures of the drawings, or in a horizontal position as shown in Fig. 5 60 of the drawings. The socket 16 when arranged either in a vertical or horizontal position, is adapted to be firmly secured to the lever 12 by means of a bolt 18, which is secured in the head 17 and projects laterally from one side thereof and is adapted to engage a hole in 65 the seat, 15, and on the threaded end of the bolt 18 is screwed a winged clamping nut, 19, which, when screwed up against the outer side of the seat 15, will securely clamp the headed end of the socket thereto. In the socket 16 is adapted to be secured a handle, 20, by 70 means of which the lever 12 is oscillated in the bearing lug 14, whereby the teeth of the segmental rack 10 thereon will engage with the teeth of the segmental gear 9 of the yoke and thereby turn or oscillate said yoke on the shaft 6 to cause the chain 8 to reciprocate 75 over the sprocket gear 5, thereby revolving the same and the dasher shaft connected thereto, first in one direction and then the other.

When the handle is arranged in a vertical position, as shown in the first figures of the drawings, the same is 80 pulled and pushed back and forth by the operator, and when the handle is arranged in a horizontal position, as shown in Fig. 5, the same is moved up and down after the manner of a pump handle.

On the outer end of the plate 2 is an upwardly projecting lug 21 on which is formed a right angularly projecting stud shaft 22. On the shaft 22 is revolvably mounted a fly wheel 23 having an inwardly extending hub on which is fixedly mounted a gear pinion 24, which is adapted to mesh with a bevel gear wheel, 25, journaled on a vertical bearing stud or shaft, 26, secured to and projecting upwardly from the base plate 2. Pivotally connected at one end to a crank pin, 27, on the wheel, 25, is a rightangularly formed pitman rod, 28, the opposite end of which is pivotally connected to the 95 upper side of the yoke, 7, to one side of the center of the same, whereby when said gear wheel 25 is turned by the movement of the fly wheel and shaft 22, the yoke 7 will be oscillated and the chain 8 reciprocated to revolve the dasher shaft and pinion, first in one direction and then the other, as hereinbefore described. If desired the fly wheel 25 may be provided on its outer side, adjacent to its outer edge, with a handle, 29, by means of which the wheel may be conveniently operated to actuate the operating mechanism.

From the foregoing description, taken in connection with the accompanying drawings, the construction and operation of the invention may be readily understood without requiring a more extended explanation.

Various changes in the form, proportion and the 110

minor details of construction may be resorted to without departing from the principle or sacrificing any of the advantages of this invention as defined in the appended claims.

5 Having thus fully described my invention, what I claim as new and desire to secure by Letters-Patent, is:

1. An operating mechanism of the character described comprising a revolvably mounted dasher shaft, a sprocket pinion on the upper end of said shaft, a sprocket chain adapted to engage said pinion to turn the same first in one direction and then the other, and means to reciprocate said chain, substantially as described.
- 10 2. An operating mechanism for washing machines, comprising a revolvably mounted dasher shaft, a sprocket pinion on the upper end of said shaft, a pivotally mounted operating yoke, a sprocket chain connected to the opposite ends of said yoke, and adapted to engage said sprocket pinion to turn the same first in one direction and then the other, and means to oscillate said yoke, substantially as described.
- 15 3. An operating mechanism for washing machines, comprising a revolvably mounted dasher shaft, a sprocket pinion on the upper end of said shaft, a pivotally mounted operating yoke, a sprocket chain connected to the opposite ends of said yoke and adapted to engage said sprocket pinion to turn the same first in one direction and then the other, an operating lever adapted to be engaged with said yoke to oscillate the same, and a handle socket adapted to be adjustably secured to said lever to actuate the same and thereby oscillate said yoke, substantially as described.
- 20
- 25
- 30

4. An operating mechanism for washing machines, comprising a revolvably mounted dasher shaft, a sprocket pinion on the upper end of said shaft, a pivotally mounted operating yoke, a sprocket chain connected to the opposite ends of said yoke and adapted to engage said sprocket pinion to turn the same first in one direction and then the other, an operating lever geared to said yoke, a handle socket, means whereby said handle socket is connected to said lever in different positions, a handle removably connected with said socket, substantially as described. 35

5. An operating mechanism for washing machines, comprising a revolvably mounted dasher shaft, a sprocket pinion on the upper end of said shaft, a pivotally mounted operating yoke, a sprocket chain connected to the opposite ends of said yoke and adapted to engage said sprocket pinion to turn the same first in one direction and then the other, a pivotally mounted operating lever geared to said yoke, a seat formed in the upper end of said lever, a handle socket having on its inner end a head adapted to be engaged with said seat to support said socket in a 40 vertical or horizontal position, a clamping bolt and nut to secure said socket and lever together in their adjusted positions, and a handle adapted to be engaged with said socket, substantially as described. 45

In testimony whereof I have hereunto set my hand in 50 presence of two subscribing witnesses.

JASPER H. STANFIELD.
